The evenly-dashed broken lines in the drawings illustrate the portions of the toy set that form no part of the claim. The lined areas shown on the inside of the toy set illustrate a contrast in color in relation to each other. The lines of the lined areas do not form part of the claimed design but rather are included merely to define the location of the lined areas. It is understood that the contrasting colors are not limited to the colors specifically indicated in the drawing disclosure. Such lined areas illustrate a contrast in appearance.
